SCREEN WALL BUILDING BLOCK

Mildred P. Bavetta, Encino, Calif., assignor, by mesne assignments, to Kaiser Steel Corporation, Oakland, Calif., a corporation of Nevada

Filed Sept. 6, 1960, Ser. No. 62,038

Term of patent 14 years

(Cl. D18—2)

FIG. 1 is a perspective view of a screen wall building block showing my new design;

FIG. 2 is a front elevational view thereof;

FIG. 3 is a side elevational view thereof; and

FIG. 4 is a plan view thereof.

I claim:

The ornamental design for a screen wall building block, substantially as shown.
